PLLC(57) **CLAIM**

The ornamental design for a solar panel assembly, as shown and described.

DESCRIPTION

FIG. 1 is a perspective view of a solar panel assembly showing our new design.

FIG. 2 is a rear view thereof;

FIG. 3 is a front view thereof;

FIG. 4 is a side view thereof;

FIG. 5 is an opposite side view thereof;

FIG. 6 is a top view thereof;

FIG. 7 is a bottom view thereof; and,

FIG. 8 is another perspective view thereof, shown in environmental use.

The broken lines shown represent the portions of the solar panel assembly that form no part of the claimed design.
